MACHINE FOR APPLYING LIQUID TO ARTICLES

Sidney J. Finn, Beverly, Mass., assignor to United Shoe Machinery Corporation, Paterson, N. J., a corporation of New Jersey

Application June 14, 1932, Serial No. 617,132

21 Claims. (Cl. 12—80)

This invention relates to machines for applying liquid to articles and is herein illustrated and described with particular reference to the applying of a liquid solvent or softener to a hard coating of cement which is carried on the margin of a sole so as to soften the cement preparatory to attaching the sole to the bottom of a lasted shoe.

In the manufacture of shoes the soles of which are attached by cement, it is customary to coat the margin of the upper or attaching face of a sole with pyroxylin cement, to allow the cement to become dry and hard, and subsequently to apply a liquid solvent to this coat of cement to activate it, the sole with the cement in this sticky state being then pressed into place upon the bottom of a lasted shoe. It is desirable that the softening liquid should be applied uniformly to the coat of cement and that application of liquid solvent to the uncoated middle portion of the forepart and to the tread face of the sole should be avoided.

To this end the invention contemplates an improved machine for applying an excess of coating material, such for example as a liquid, to a sole having the face to which the coating is applied diverging from the horizontal, said machine including means for applying the coating progressively to localities on the sole above its lower edge, allowing the excess to drain from the sole without soiling the tread surface, and provided with mechanism for moving the sole in a novel manner to cause the liquid to be applied along a substantially uniform width of the cement-coated margin thereof. In this way the liquid solvent tends always to run by gravity down the margin of the sole and is prevented from reaching either the uncoated middle portion of the forepart of the sole or the tread face of the sole.

According to one feature of the invention there is provided a liquid-applying member, and novel means for maintaining a shoe sole in operative relation thereto and inclined to the horizontal, and, while so maintained, moving it past the applying member. In the illustrated construction, a sole is grasped loosely near its heel end by grippers which are mounted upon a traveling carrier; and then the carrier is moved first so as to move the edge of the sole over a gage beside the applying member to apply liquid progressively along one edge of the sole, then along the curved edge at the toe portion, and then along the other edge of the sole. To accomplish this the carrier is moved first bodily in a direction lengthwise of the sole, is then swung about one of its ends through 180°, and is then moved bodily in the

same direction as that of the first movement. And, in order to make sure that sufficient liquid solvent shall be applied, the cycle of movement outlined above is then repeated in the reverse direction so that a second coat of solvent is applied over the first coat. 5

Inasmuch as the carrier swings about one of its ends, it is desirable that the toe end of the sole should be made to register with this end. In accordance with another feature of the invention 10 the grippers, which grasp the sole or other article, are adjustable with respect to the traveling carrier. In the illustrated construction the grippers are carried by a bracket which is adjustably mounted upon the carrier, and means are provided for temporarily disconnecting the gripper bracket from the carrier to permit relative adjustment of these two members so that soles of different lengths may be placed in the machine with their toe ends in register with that end of 20 the carrier about which the swinging movement takes place.

The illustrated machine including certain details of construction and combinations of parts will now be described and pointed out in the appended claims. 25

Referring now to the accompanying drawings, Fig. 1 is an end elevation of a machine in which the present invention is embodied, certain parts having been broken away;

Fig. 2 is an elevation of a portion of the front of the machine showing more particularly how the traveling sole carrier is swung through 180°;

Fig. 3 is a front elevation of the machine with the front cover plate and the hand-wheel removed, the shaft 51 being shown in section;

Fig. 4 is a detail principally in section showing the starting mechanism in position to be operated to start the machine;

Fig. 5 is a detail of the same parts shown in 40 Fig. 4 but in the positions occupied by them while the machine is running;

Fig. 6 is a vertical section taken on the line VI—VI of Fig. 8 viewed from the back of the machine showing all of the machine except the 45 liquid-applying mechanism;

Fig. 7 is a plan of a sole showing the locality along the margin to which liquid is applied;

Fig. 8 is a plan view of the machine;

Fig. 9 is a detail showing how the sole is supported at the toe portion while it is being swung;

Fig. 10 is a detail of the latch which holds the brush-driving clutch in engagement while the machine is running;

Fig. 11 is a detail of the mechanism for controlling the brush-driving clutch;

Fig. 12 is a detail in plan of the gripper bracket and a portion of the traveling carrier;

5 Fig. 13 is an elevation of the treadle-operated mechanism;

Fig. 14 is a vertical section of this mechanism on the line XIV—XIV of Fig. 13; and

10 Fig. 15 is a view partly in elevation and partly in section of a substitute mechanism for the brush by means of which the liquid may be flowed upon the sole instead of being brushed upon it.

15 Before proceeding to a detailed description of the machine a brief description of its purpose and mode of operation will be given. The general purpose of the machine is to apply a coating of liquid to a selected portion of an article; and the illustrated machine is particularly adapted to apply a liquid solvent to a hard coating of 20 pyroxylin cement which is carried on the margin of the flesh surface of a sole so as to soften the cement preparatory to attaching the sole to the bottom of a lasted shoe. Referring to Fig. 7 there is shown a molded sole 100 having thereon a hard 25 coating of cement which extends from a point near the heel end of the sole along one margin of the sole, around the toe, along the other margin, and back to a point opposite the first point.

30 Referring first to Fig. 8, the sole is placed in the machine, as shown, with the heel end engaged loosely by grippers 71 which are carried in a manner presently to be described by an elongated traveling carrier 19 made hollow to decrease its weight and to permit it to be readily actuated. 35 The sole is on edge so as to be inclined to the horizontal, and a rotary brush 20 supplied with liquid engages the lower margin of the sole near the heel end and is rotated crosswise of the sole to apply liquid from a locality on the face of the sole toward and to an edge thereof. The brush is caused to act upon the sole in this manner so as to ensure that the liquid will always run down toward an edge of the sole and will be prevented from reaching the middle portion 300 (Fig. 7) 40 of the forepart of the sole. A rest or gage 203 (Fig. 6) keeps the edge of the sole in the desired relation to the brush thereby to treat a marginal portion of substantially uniform width while a roller 22 holds the sole against the brush. Referring now to Fig. 3 it will be seen that the toe end of the sole 100, when properly positioned preparatory to starting the machine, is in register with the rounded end of the traveling carrier 19. The sole having been thus placed in the 45 machine, the carrier first moves horizontally to the left as viewed in Fig. 3, then rotates 180° clockwise about its rounded toe end, and then moves horizontally to the left again until the brush is operating upon what was the upper margin of the heel portion of the sole but is now the 50 lower margin. Liquid has thus been applied over the entire margin of the sole except at the heel end; and the carrier is in an extreme left-hand position. The cycle of movement, which has just 55 been described, is then reversed to apply a second coat to the same margin of the sole. In this second cycle, which takes place in the reverse direction, the carrier moves first to the right, then swings counterclockwise 180° about its rounded 60 toe end, and then moves again horizontally to the right and comes to rest in the position shown. The margin of the sole thus receives two applications of liquid extending from a locality on one side of the sole near the heel end thereof, 65 around the toe portion and back to a locality

near the heel end opposite to the locality at which the application began.

Referring now to Figs. 3 and 8, there may be seen the construction of the traveling sole carrier 19, upon which a gripper carrying bracket 5 71 is adjustably mounted in a manner and for a purpose later to be described, consists of an open-sided member having a normally horizontal upper wall 19¹; and a normally horizontal lower wall 19² connected at their right-hand ends by 10 a curved wall 19³, and a vertical back wall 19⁴. This traveling carrier normally occupies the position shown (Fig. 3), when the machine is at rest, with the lower wall 19² resting upon two rubber-covered rolls 21 (see also Fig. 1) fast 15 respectively to shafts 23, 23 which have fast respectively to their outer ends pinions 25, 25. Located inside the hollow open-sided traveling carrier 19 is a small rubber-covered presser roll 27 loosely mounted by means of a ball bearing upon a stub 20 shaft 29. This stub shaft (Figs. 1 and 2) is carried at the outer end of a slide 31 which is vertically 25 slideable on the front cover plate 33 of the machine in guide brackets 35. The vertical slide is also guided by a pin 37 which extends into 30 a vertical slot 39 in the slide. A compression spring 41 rests with its upper end against a stationary lug 43 on the cover plate and with its lower end upon the upper end of an adjusting screw 45 threaded through the lower portion of 35 the slide 31 into the slot 39. The small presser roll 27 thus engages at all times some locality on the straight wall 19¹, the straight wall 19² or the curved connecting wall 19³, said three walls 40 really forming a continuous wall or flange of 35 elongated U-shape, and exerts at all times a downward thrust, the force of which may be varied by turning the adjusting screw 45. Consequently, when the pinions 25 are both rotated in one direction, the traveling carrier 19 is first 40 moved horizontally in one direction by the rolls 21 until the curved portion at the end of the carrier is encountered by the small presser roll 27 whereupon the carrier is swung through 180° 45 about its curved end and is then moved again 50 horizontally in the same direction. As will presently be explained, the direction of rotation of the pinions 25 is then automatically reversed and the traveling carrier then goes through a second 55 cycle of movement in a direction which is the reverse of that of the first cycle. When the curved end of the traveling carrier 19 is encountered by the small presser roll 27, said roll pushes this 60 curved end down to some extent into the space between the rubber covered driving rolls 21; and in order to insure that the wall of the carrier 19 shall be firmly gripped during the swinging movement of the carrier which then ensues, a 65 filler piece 47 (Fig. 2) is located in the curved end of the carrier.

60 For the actuation of the sole carrier, the pinions 25 (Fig. 3) are driven by a large gear 49 fast to a rotary shaft 51 to which is also fast a second large gear 53, said last-named gear meshing with a worm 55 fast to a horizontal shaft 57 65 which is mounted for rotary and longitudinally sliding movement in a bracket 59, the pivotal mounting of which on the frame of the machine will be described later. Fast to the shaft 57 is a large middle clutch member 61, and loose upon 70 this shaft are two smaller clutch members 63, 65, one on each side of the large clutch member 61. A round belt 67, driven continuously from a suitable source of power and extending around 75 pulleys formed on the surfaces of the small clutch

members and around a small idler 69 runs in the direction indicated by the arrows and thus rotates the two small clutch members respectively in opposite directions. In the position of the parts shown in Fig. 3 the shaft 57, together with the large clutch member 61 has just been pushed to the right from its neutral middle position into contact with the small clutch member 65, and the machine is just starting. The traveling carrier 19 will move to the left until the curved end 19³ is reached. It will then swing clockwise about said curved end and afterward move again to the left thus completing the first cycle. At this time the shaft 57 with the large clutch member 61 will be moved to the left so as to be driven by the small clutch member 63, whereupon the traveling carrier 19 will go through its second cycle in a direction the reverse of that of the first. At the end of this second cycle the parts will be once more in approximately the position shown in Fig. 3 except that the large clutch member will be in neutral position and the machine will be at rest.

Before describing in detail how the machine is started and how the direction of rotation of the driving shaft with its worm 55 reversed, a description of how the sole is located initially with its toe end in register with the curved end of the traveling carrier 19 will be given. During the operation of the machine, as has been described, the sole is held (Fig. 8) rather loosely by the grippers 71 so that it can pivot in the carrier sufficiently to always ride on the gage 209. These grippers are pivoted at 73 to a gripper bracket 77 and urged toward each other at all times by a tension spring 75 which is fastened at one end to the tail of one gripper and at the other end to the tail of the other gripper. Referring now to Figs. 12, 13 and 14, this gripper bracket 77 has a horizontally extending guideway to receive a horizontally extending guide bar 79 rigid with the traveling carrier 19, so that the traveling carrier may be adjusted with respect to the gripper bracket when a sole is placed in the machine prior to starting the machine, such an adjustment being necessary in view of the wide variation in the extreme sizes of shoe soles, in order to cause the toe end of the sole to register with the curved end of the traveling carrier 19 about which the carrier and the sole are rotated through 180° in the manner which has been described above.

The gripper bracket 77, supporting the grippers 71 by which the sole 180 is caused to follow the carrier 19, is releasably locked to the guide bar 79 of the traveling carrier 19 by a small vertically movable block 81 having teeth on its upper edge which may be forced into engagement with teeth 83 formed on the lower edge of the guide bar 79. In Figs. 12, 13 and 14 the parts are shown in the positions occupied by them when the machine is at rest and before a sole has been placed in the machine. In this position of rest, the small locking block 81 is held up in engagement with the guide bar 79 by a cam 85 pivoted at 87 to the gripper bracket and held in the angular position shown by a leaf spring 88. This cam 85 has a horizontal finger which extends into a vertical slot 89 in a vertical slide bar 91 to the lower end of which is attached a treadle rod 93 which is urged upwardly at all times by the horizontal arm of a bell-crank lever 94 pivoted at 96 to the frame of the machine. This lever is shown complete in Fig. 6 where it will be seen that it is urged at all times to rotate about its pivot 96 by means

of a tension spring 98 and that a stop 102 limits its movement in a counterclockwise direction. Referring again to Figs. 12, 13 and 14, the gripper bracket is not only locked to the traveling carrier 19 but is also held from longitudinal movement in either direction so that, if the treadle rod 93 is pulled down far enough to swing the cam 85 in a clockwise direction (Fig. 14) by engagement of the finger on the cam with the upper inclined wall of the slot 89 to disconnect the gripper bracket from the traveling carrier 19, the carrier may be adjusted horizontally with respect to the gripper bracket. When the traveling carrier 19 has thus been disconnected from the gripper bracket 77 (and also as will presently be explained from its driving mechanism) the traveling carrier 19 may be adjusted horizontally to cause its curved end to register with the toe end of a sole which the operator has placed in the machine.

To this end, referring now more particularly to Fig. 13, the gripper bracket is held from movement to the left by contact with an abutment which will be described later. It is held temporarily from movement to the right by a catch 95 which engages a downturned lug on the gripper bracket 77, said catch being pivoted at 97 to the frame and being urged upwardly at all times by a compression spring 99. A link 101 furnishes means for pulling the catch down at the proper time to release the gripper carrier 77, this link being pivoted at its upper end at 103 to the catch and having near its lower end a vertical slot 105 to receive a horizontal pin 107 carried by a second vertical slide bar 109. This second vertical slide bar has a lost-motion connection with the vertical slide bar 91 through the horizontal arm of the bell-crank lever 94 which extends through a comparatively wide opening in the side of the slide bar 109, the rounded end 40 of the horizontal arm being received in a small opening in one side of the slide bar 91.

When the treadle rod 93 is pulled down, the first part of its downward movement swings the cam 85 (Fig. 14) to unlock the gripper bracket 77 from the traveling carrier 19 as has been explained, the slide bar being held in this part-way-down position while the traveling carrier 19 is being adjusted to cause its rounded end to register with the toe end of a sole. After this adjustment has been made, the slide bar 91 is pulled all the way down. During the last part of this movement, the downward swinging horizontal arm of the bell-crank lever 94 (Fig. 13) strikes the lower wall 111 of the opening in one side of the vertical slide bar 109 and pulls that bar down, thereby presently pulling down the link 101 and with it the catch 95 so that the gripper carrier 77 is unlocked and the machine may be started. At the same time that the catch 95 is 60 swung down, the grippers 71 (Fig. 12) are permitted to close upon the heel end of the sole by the pulling down of a pin 112 which is normally in raised position and holds the grippers open as shown, this pin (Fig. 13) being carried by an angle iron 113 which is fastened by screws 114 to the slide bar 109. As the traveling carrier 19 with the gripper bracket 77 approaches the end of its second-cycle of movement, the divergent faces 115 of the grippers 71 straddle the pin 112 70 and are opened by the time the machine comes to rest.

The operator-controlled slide bar 91, as has been explained, is first pulled down part way and held there while the initial position of the travel-

ing carrier 19 is being adjusted. It is then pulled all the way down to pull down the slide bar 109 which disconnects the catch 95 from the gripper bracket and pulls down the pin 112 to permit the 5 spring 75 to close the grippers upon the heel end of a sole which is being held in position by the operator. The slide bar 91 is then released by the removal of the foot of the operator from the treadle 114 (Fig. 1) which is connected to the 10 lower end of the treadle rod 93, and the slide bar 91 rises, but the slide bar 109 does not rise at this time. It rises, as will presently appear, when the direction of rotation of the driving worm 55 (Fig. 3) is reversed. With regard to the effect 15 of the movements of the slide bar 91 (Fig. 14) the first effect is to engage the finger on the cam 85 which rides up the inclined wall of the slot 89 and then rides up the flat face of the bar 91. When the slide bar 91 is released and returns to 20 the position shown, the cam 85, under the influence of the spring 88, resumes the position shown, and the gripper bracket 77 is once more locked to the carrier 19 so that it will move with said carrier when the carrier is actuated.

25 It has been explained above that when the treadle is depressed to pull the slide-rod 91 part way down, the gripper bracket 77 is disconnected from the traveling carrier 19 though still held from movement so that said carrier may be adjusted horizontally with respect to the gripper bracket. This horizontal adjustment is accomplished by turning the hand wheel 116 (Fig. 8) which is fast to the shaft 51; but this of course can not be done until the gear 53 (Fig. 3) is disconnected from its driving worm 55. Provision is therefore made for disconnecting the worm 55 from the gear 53 when the slide bar 91 is pulled down. To this end, the casting 59 in which the shaft 57 is mounted for rotary and 40 sliding movement, is mounted for swinging movement about the axis of a horizontal rock-shaft 117, the casting being fast to one end of said rock-shaft which has bearings in the frame of the machine, as best shown in Fig. 8. Returning now to Fig. 3, a compression spring 119 normally holds the casting 59 in the position shown with the driving shaft 57 horizontal and the worm 55 in mesh with the gear 53. In order to swing the casting down about the axis of the 45 rock-shaft 117 when the treadle rod 93 is pulled down part way, there is fast to said treadle rod a collar 121 having a hook to which the lower end of a heavy tension spring 123 is attached, the upper end of the spring being attached to a hook 50 on one end of the casting 59. Consequently, when the treadle rod is pulled down part way, as has been described, to free the gripper bracket from the traveling carrier 19, the worm 55 is disconnected from the gear 53 so that the operator may 55 turn the shaft 51 freely in either direction to adjust the traveling carrier into the proper initial position with respect to the sole 100.

60 In order to facilitate bringing the toe end of the sole into register with the rounded end of the traveling carrier 19 during this adjustment, a locator in the form of a plate 125 is provided. When the operator places a sole in proper position in the machine and holds it there while he depresses the treadle part way to unlock the gripper bracket from the carrier 19 and to disconnect the worm 55 from the gear 53, this locator 125 is swung yielding to the left (Fig. 3) until it contacts either with the toe end of the sole or with the rounded end of the carrier 19 depending upon the length of the sole and the position

which the carrier occupies. If the locator 125 is in contact with the toe end of the sole it remains stationary, while the carrier is adjusted to the right. If the locator is in contact with the rounded end of the carrier, it follows the carrier during the adjustment of the carrier to the left. In either case the traveling carrier 19 is adjusted until both the toe end of the sole and the rounded end of the carrier are in contact with the locator. This locator 125 is fastened by a 10 bracket 126 to the upper end of a bent lever 127 pivoted at 129 to the frame and at its lower end to the right-hand end of a horizontal link 131, the left-hand end of which is pivoted at 133 to the lower end of the vertical arm of a bell-crank 15 lever 135, the outer end of the horizontal arm of which is fast to the upper end of a tension spring 137. The lower end of the spring 137 is fast to a hook carried by the collar 121 on the treadle rod 93. The locator 125 is normally held in its outer, 20 inoperative position by a tension spring 139 fast at one end to the lever 127 and at the other end to the frame. When the treadle rod 93 is pulled down, the locator 125 is swung to the left until it contacts either with the rounded end of the 25 carrier 19 or with the toe end of a sole, this movement resulting because the spring 137 is somewhat stronger than the spring 139. It should be noted however, that, because of the presence of these two springs this locator may still yield in 30 both directions. If therefore it is in contact with the rounded end of the carrier, it will follow the initial adjusting movement of the carrier in whichever horizontal direction the carrier may be adjusted. It will also of course follow any movement of the sole if it is in contact with the toe end of the sole and the operator moves the sole to the right or left.

While the operator holds the treadle rod 93 part way down, he turns the shaft 51 by manipulating the hand wheel 116 with one hand while, with the other, he holds the sole 100 in proper position with respect to the sole grippers, which are open at this time. He then pushes the treadle all the way down and releases it. The machine 45 is then ready to start, the traveling carrier 19 having been adjusted into the proper position, the grippers having been closed on the sole, the gripper bracket having been again locked to the traveling carrier 19 and having been unlocked 50 from the frame, and the worm 55 having been swung up into mesh with the gear 53. The machine however does not start until a lever 141 has been swung up by the operator.

55 This starting lever and the mechanism for automatically reversing the direction of rotation of the shaft 57 are connected and will be described together. Referring to Figs. 3, 4 and 5, the machine is started by pushing the shaft 57 to the right thereby moving the large clutch member 61 into the position shown in which it is pressed against the small clutch member 65. This movement does not result from depression of the treadle. Instead, depression of the treadle stores up energy in a compression spring 143 (Fig. 4) 60 at the left-hand end of the shaft 57 so that, when the lever 141 is swung up, this energy is released to move the shaft to the right and thereby start the machine, with the shaft gears and pinions rotating in the directions indicated by the 65 arrows. This movement continues until the first cycle of movement of the traveling carrier 19 is completed, whereupon the shaft is moved to the left to reverse the direction of rotation of the shaft, gears and pinions so as to cause the second 70

75

cycle of movement of the carrier to take place in the reverse direction.

Referring again to Fig. 4, the spring 143 is located in a sleeve 145 slidably mounted on the frame of the machine, said slide having extended into it a cylindrical plunger 147. The sleeve has a solid head at its right-hand end which contacts with a small ball carried at the left-hand end of the shaft 57. The plunger 147 is pivoted at its left-hand end at 149 to one end of one member 150 of a toggle, the knuckle of the toggle being indicated at 151 and the other member 152 of the toggle being fast to a rock shaft 153. If now the toggle is straightened, as shown, while the sleeve 145 is held stationary, the plunger 147 will compress the spring 143 and thereby load it by storing up energy in it so that, when later the sleeve 145 is released, the stored up energy in the spring will move the sleeve and with it the shaft 57 and large clutch member 61 to the right. The toggle is straightened by an abutment 155 which is integral with the vertical slide rod 109, said rod, as has been explained, having been moved down into the position shown when the treadle was depressed. The sliding sleeve 145 is held stationary during the straightening of the toggle by an auxiliary toggle comprising a member 157 pivoted at its right-hand end 159 (Fig. 4) to the frame and a second member which is part of the bell-crank lever 141 and is pivoted to a lug on the sliding sleeve 145 at 161, there being a tension spring 163 which tends at all times to urge this auxiliary toggle into the straightened position shown. If now the lever 141 is swung clockwise the auxiliary toggle will be broken, and the loaded spring 143 will act to push the shaft 57 to the right and start the machine. The parts are shown in this position in Fig. 5.

In order to move the shaft 57 to the left so as to reverse its direction of rotation at the proper time, a mechanism much like that shown in Figs. 4 and 5 is provided except that there is only one toggle. Referring to Fig. 3, there is at the right-hand end of the shaft 57 a sliding sleeve 165, a spring 167, a plunger 169 and a toggle comprising members 171, 173, the latter member being fast to a rock shaft 175 to which is also fast the lower end of an upright arm 177. The upper end of this arm is pivoted at 179 to one end of a horizontal link 181, the other end of which is pivoted at 183 to an upright arm 185 pivoted at its lower end at 187 to the frame and at its upper end at 189 to the right-hand end of the long horizontal link 191. The left-hand end of the long link 191 is pivoted to the upper end of an upright arm 193, the lower end of which is pivoted to the frame at 96. In order to hold the linkage just described, normally in the position of the parts as shown in Fig. 3 with the toggle 171, 173, broken, a tension spring 197 is fast at its left-hand end to a pin on the link 181 and at its right-hand end to the frame. This linkage which, as will presently appear, operates to straighten the toggle 171, 173 at the right-hand end of the shaft 57, operates also to break the toggle at the left-hand end of the shaft. To this end, there is pivoted to the upright arm 193 one end of a horizontal link 199, the other end of which has a lost-motion pin-and-slot connection with the upper end of an arm 201 which is fast to the rock shaft 153 to which is also fast the member 152 of the toggle 150, 152.

In order to move the long link 191 to the left (Fig. 3) at the proper time so as to reverse the direction of rotation of the shaft 57 and hence to

reverse the direction of movement of the carrier 19, said link 191 has fast to it an abutment 203 with the right-hand side of which a lug 205 (see also Fig. 6) on the gripper bracket 77 contacts at the end of the first cycle of movement 5 of the traveling carrier 19. When the sole is about to finish its movement to the left at the end of the first cycle, this lug strikes the abutment 203 and moves the link 191 to the left (Fig. 3). This straightens the toggle 171, 173 at the right-hand 10 end of the shaft 57 and compresses the spring 167. Movement of the long link 191 to the left also moves to the left the horizontal link 199 near the other end of the shaft 57; and presently the right-hand end of the slot in this link engages the 15 pin at the upper end of the arm 201 and breaks the toggle 150, 152 whereupon the auxiliary toggle composed of the link 157 (Figs. 4 and 5) and the horizontal portion of the bell-crank lever 141 is straightened by the spring 163, the upward 20 breaking of the main toggle 150, 152 acting through the abutment 155 to push up the slide bar 109 which was previously pulled down when the treadle was depressed. As soon as this toggle 150, 152 is broken, the compressed spring 167 at 25 the other end of the shaft 57 pushes that shaft to the left to force the clutch member 61 against the small clutch member 63 so as to reverse the direction of rotation of the shaft. The extent of longitudinal movement of the shaft 57 is very 30 small and is not prevented by the mesh of the worm 55 with the gear 53, this mesh being a loose one.

The same long horizontal link 191 (Fig. 3), movement of which in one direction reverses the 35 direction of rotation of the shaft 57, is moved in the other direction at the proper time and to the proper extent to break the toggle 171, 173 and thus stop the machine. To this end, there is an upward extension 207 at the left-hand end of the 40 link 191 with which a second lug 205' on the gripper bracket contacts just before the completion of the second cycle of movement of the sole when the gripper bracket is moving to the right. This pushing of the link 191 to the right 45 acts through arm 185, link 181, and arm 177 to break the toggle 171, 173 and thereby allow the compressed spring 167 to expand so that the large middle clutch member 61 is no longer held against the small clutch member 63. The lug 50 205 on the gripper bracket 77 which contacts with the abutment 203 to reverse the direction of rotation of the shaft 57 at the end of the first cycle is clearly shown in Fig. 6; and in the same figure appears the extension 207 on the link 191 which 55 is engaged by the second lug 205' on the gripper bracket to stop the machine at the end of the second cycle. It is this extension 207 which, in cooperation with the catch 95, holds the gripper bracket from movement in either direction when 60 the machine is at rest, the vertical slide bar 109 having then been moved up, by the push of the toggle 150, 152 on the abutment 155, to permit the spring 99 (Fig. 13) to swing the catch 95 up into engagement with the gripper bracket 77 as 65 has been described.

When the traveling carrier 19 is being swung through 180° in the course of its movement, as shown in Fig. 9, its curved end is pushed down to some extent into the space between the rubber 70 covered rolls 21. The stationary rest or gage 299, before mentioned, supports the extreme toe edge of the sole but it is desirable to provide means for engaging the side edges of the sole adjacent to the toe end to prevent the toe portion 75

of the sole from being displaced sidewise. To this end two guide fingers 211, 213 are temporarily moved into the position shown in Fig. 9 to aid in supporting the toe end of the sole. These fingers (Fig. 8) are the two arms of a yoke pivoted about a horizontal axis 215, said yoke having a tail 217 which is engaged by the rounded end of the traveling carrier 19 during this swinging movement so that during said movement the fingers 10 are swung up into the position shown in Fig. 9. As soon as the carrier resumes its horizontal position, the fingers 211, 213 drop out of the way.

The applying brush 20 (Fig. 1) is fast to a rotary horizontal shaft 231 to which is also fast 15 a pinion 233 driven by a worm 235 on one end of a small rotary horizontal shaft 237, said brush dipping into a solvent liquid 500 in a shallow container in which the level of liquid is maintained uniform by a barometric feed device indicated 20 as a whole by the reference numeral 239. This barometric feed device may be of a suitable form, and the details of its construction will not be described. A drain pipe 240 provides means for drawing off the liquid in the chamber just below 25 the barometric feed device any time after the device has been removed.

It is desirable that the brush 20 should not rotate continuously but substantially only when the machine is running. In the illustrated construction the brush starts its rotation when the treadle of the machine is depressed and stops when the machine comes to rest. To this end the small brush shaft 237 (Figs. 8 and 11) has loose and slidably upon it a clutch pulley 241 driven continuously by means of a belt 242 from any suitable source of power, said pulley being urged at all times away from a clutch member 243, which is fast to the shaft 237, by a compression spring 244, there being between the pulley and the clutch member a friction washer 245. The clutch pulley 241 has an extension on the side opposite to the clutch member 245 which extends into the cupped end of a sleeve 246 which is loose and slidable on the shaft 237. This sliding sleeve 246 (Fig. 11) has a pair of flat localities 30 near one end to receive the upright arms 247 of a yoke in the form of a bell crank lever pivoted at 248 to the frame and having a horizontal arm to the outer end of which is fast the upper end 35 of a tension spring 251, the lower end of this spring being attached to the right-hand end of an arm 254 the hub of which is fastened to the far end of a small rock-shaft 255, as viewed in Fig. 11. To the near end of this rock-shaft is fastened 40 the hub of a second arm 253 the outer end of which is located above the right-hand end of the tail of the treadle 114 of the machine so that, when this treadle is depressed, the clutch is thrown in. A compression spring 257 acts at 45 all times upon the upright portion of the bell crank lever 247 to swing said lever counterclockwise about its pivot 249 and thus tends at all times to throw out the clutch.

With the construction as thus far described, if 50 the treadle 114 were released, the clutch would be immediately thrown out. Inasmuch, however, as the treadle is released, as has been described, just before the machine is started, means are provided for holding the clutch operative when 55 the treadle is released. This means is a latch 259 (Fig. 10) pivoted to the frame at 261' and urged to rotate clockwise about said pivot by a compressed spring 263. When, therefore, the treadle 114 is depressed and the clutch thrown in, the lower end of the latch 259 moves into posi-

tion over the horizontal arm of the bell crank 247 so that, when the treadle is released, the clutch remains operative. It remains thus until just prior to the time when the machine comes to rest at which time the latch 259 is tripped 5 by being rotated counterclockwise (Fig. 10) to permit the horizontal arm of the bell crank 247 to swing up and release the clutch. The latch 259 is tripped by a long lever 261 (Fig. 8) pivoted to the frame at 263' and normally held yieldingly 10 in the position shown by a small tension spring 265 fast at one end to the lever and at the other to the frame. This long lever extends from the back of the machine, where the latch 259 is located, to the front of the machine, its forward 15 end being located adjacent to the long link 191 longitudinal movement of which first in one direction and then in the other first reverses the direction of rotation of the shaft 57 and then brings the machine to rest as has been described 20 above. At the forward end of the long lever 261 is pivoted a one-way latch 267 held normally in the position shown by a leaf spring 269, said latch being adapted to cooperate at the proper time with a small abutment 271 carried by the long 25 link 191.

With the parts of the machine occupying the positions shown in Fig. 8, the machine is just starting. When the first cycle of the traveling carrier 19 is about to be completed, the direction of rotation of the shaft 57 of the machine will be reversed, as has been described, by a lug 205 (Fig. 3) on the gripper bracket 77, which lug engages the abutment 203 on the link 191 and pushes the link to the left. This movement of 30 the link will carry the small abutment 271 (Fig. 8) past the small latch 267 on the long lever 261. In this movement of the abutment 271, the small latch will be swung clockwise by the moving abutment 271 but will presently be returned 40 to the position shown by the leaf spring 269 when the small abutment 271 has moved past the latch. During these movements the long lever 261 will not be swung about its pivot 263'. The machine now goes through its second cycle; and just at 45 the end of this cycle the long link 191 will be moved to the right to stop the machine. During this movement to the right the small abutment 271 will again engage the latch 267, which cannot then swing about its pivot, and will therefore 50 swing the long lever 261 counterclockwise (Fig. 8) so that its rear end (Fig. 10) will swing the latch 259 and thereby release the bell crank lever 247 whereupon the compression spring 257 (Fig. 11) will throw out the clutch, and the liquid-applying 55 brush 20 will come to rest.

The various mechanisms of the machine and their modes of operation have been described above individually and in small groups. A brief description of the operation of the machine as a 60 whole will now be given. Assuming that the machine is at rest with the grippers 71 open, the operator first places a sole in the machine in the desired position and depresses the treadle part way. This disconnects the worm 55 (Fig. 3) from 65 the gear 53, swings the locator 125 into contact either with the toe end of the sole or with the rounded end of the carrier 19, and unlocks the gripper bracket 77 (Figs. 13 and 14) from the carrier 19. The operator, while still holding the sole 70 with one hand, turns the hand wheel 116 (Figs. 1 and 8) with the other hand to cause the toe end of the sole and the rounded end of the carrier 19 to come into register. He next pushes the treadle all the way down to pull down the slide 75

109 (Figs. 13 and 14) whereby the pin 112 is pulled down to permit the grippers 71 to close upon the sole. During the same downward movement of the slide 109, the gripper bracket 77 is freed from the carrier 19 by pulling down the catch 95, and the abutment 155 straightens the toggle 150, 152 (Fig. 4) thereby compressing the spring 143. Depression of the treadle has by this time started rotation of the brush 20 through the lever 253 (Fig. 11), and the latch 259 (Fig. 10) has swung into the position shown to insure that the brush will continue to rotate when presently the treadle is released. The operator now releases the treadle, whereupon the slide 91 (Figs. 13 and 14) is moved up so that the gripper carrier 77 is again locked to the carrier 19 and the worm 55 (Fig. 3) is swung up into mesh with the gear 53. The brush is now rotating and the machine ready to start. The operator swings the lever 141 (Fig. 4) to break the auxiliary toggle which has thus far held the sliding sleeve 145 from movement, and the compressed spring 143 expands to press the large clutch member 61 against the small clutch member 65. The traveling carrier 19 now moves to the left (Fig. 3) dragging the edge of the sole over the gage 209 until the rounded end of the carrier encounters the presser roll 27 whereupon the carrier swings clockwise through 180° and then moves again to the left. Just prior to the end of the left-hand movement, the lug 205 (Fig. 6) on the gripper bracket 77 strikes the abutment 203 (Fig. 3), due to the fact that the carrier 19 has been rotated 180° from the position shown, and moves the long link 191 to the left, as viewed in that figure. This straightens the toggle 171, 173 at the right-hand end of the shaft 57 thereby compressing the spring 167 and breaks the toggle 150, 152 at the left-hand end of the shaft so that the expansion 40 of the spring 167 moves the shaft to the left and reverses its direction of rotation. The breaking of the toggle 150, 152 at the left-hand end of the shaft 57 pushes up the abutment 155 and with it the slide 109 (Fig. 13) to effect upward movement of the pin 112 into operative position whereby it will later open the grippers, and the catch 95 swings up into operative position later to engage the gripper carrier. The traveling carrier (Fig. 3) moves to the right until its rounded 50 end encounters the presser roll 27 again whereupon the carrier swings counterclockwise through 180°. During this swinging movement, as in the former swinging movement, the fingers 211, 213 (Fig. 9) are temporarily moved up into contact with the side edges of the sole adjacent to the toe end and beside the gage 209. The traveling carrier then moves again to the right (Fig. 3). Just prior to the end of this movement, the gripper bracket strikes the extension 207 of the long link 191 and moves that link to the right to break the toggle 171, 173 at the right-hand end of the shaft 57 so as to stop the rotation of that shaft. During this last part of the movement of the carrier 19 to the right, the grippers 77 are opened by engagement of the pin 112 (Fig. 12) with the divergent faces 115 on the grippers. Movement of the link 191 to the right (Fig. 8) also stops the rotation of the brush 20 when the small abutment 271 on the link 191 engages the latch 267 on the forward end of the lever 261 and swings said lever counterclockwise to disconnect the clutch which drives the brush. The machine thus comes to rest with the sole coated as indicated in Fig. 7 and the grippers open ready to

allow removal of the sole just treated and its replacement by another sole.

In Fig. 15 there is shown a liquid applying member which may be substituted for the brush so as to flow liquid upon the sole instead of brushing it on. In this form of the invention, the brush, its mounting, and the barometric feed are replaced by a receptacle 273 for liquid having leading from its bottom a pipe 275 located to deliver liquid upon one face of the sole at a locality 10 near the lower edge thereof. A valve 277 provides means for controlling the flow of liquid, and a drain pipe 279 permits the liquid to be drawn off when desired from the shallow receptacle 281 which receives the drip from the pipe 275. The 15 mechanism for carrying the sole past the outlet of the pipe 279 is the same as that described above for carrying the sole past the brush, certain parts of this mechanism such as the traveling carrier 19, the presser roll 27 which engages the 20 carrier, the sole-engaging roll 22, and the sole edge gage rest 209 being shown. In this form of the invention, the operator opens the valve 277 just prior to starting the machine and closes it when the machine comes to rest. 25

Referring now to Fig. 7 and bearing in mind that the sole is maintained on edge during the application of liquid and that the liquid is always applied in such a way that it tends to run by gravity toward an edge of the sole, it will be seen 30 that the middle portion 300 of the forepart of the sole is kept free from liquid, and that the coating is applied only along the desired portion of the margin.

Applicant makes no claim herein to any subject-matter common to this application and an application filed March 28, 1933, Serial No. 663,121, on behalf of Ernest W. Stacey upon a machine for applying cement to the marginal portion of a tennis shoe for the attachment of a 40 foxing.

Having thus described my invention, what I claim as new and desire to secure by Letters Patent of the United States is:

1. A machine of the class described having, in 45 combination, a container for liquid, a liquid-applying member supplied therefrom, and a carrier for a shoe sole mounted for swinging movement about a center adjacent to one of its ends in a plane substantially parallel to the plane of the 50 sole to present successive portions of the margin of the sole to the applying member, said carrier having sole-gripping means, said gripping means being adjustably mounted on the carrier to permit soles of different lengths to be held thereon 55 with one end in register with said end of the carrier.

2. A machine of the class described having, in combination, a container for liquid, a liquid-applying member supplied therefrom, means for 60 gripping a shoe sole, an elongated carrier for the gripping means mounted for swinging movement about an end corresponding to an end of the sole thereon, said carrier and said gripping means being relatively adjustable to provide for soles of 65 different lengths, a locator for facilitating proper relative adjustment of the gripping means and the carrier to bring the end of the sole into a predetermined relation to the end of the carrier, and means for imparting movement to the carrier and 70 gripping means to cause the sole to move past the liquid-applying member.

3. A machine of the class described having, in combination, a container for liquid, a liquid-applying member supplied therefrom, means for 75

gripping a shoe sole, an elongated carrier for the gripping means mounted for bodily movement and for swinging movement about an end corresponding to an end of the sole thereon, said carrier and said gripping means being relatively adjustable to provide for soles of different lengths, a locator for facilitating proper relative adjustment of the gripping means and the carrier, and means for imparting bodily and swinging movements to the carrier and gripping means to carry the periphery of the sole past the liquid-applying member.

4. A machine of the class described having, in combination, a container for liquid, a liquid-applying member supplied therefrom, means for gripping a shoe sole, a movably mounted carrier for the gripping means, said carrier and said gripping means being relatively adjustable to provide for soles of different lengths, a locator adapted yieldingly to engage an end of the carrier and an end of the sole when the two have been brought into registration, and means for imparting bodily movement to the carrier and gripping means to cause one side of the sole to move past the liquid-applying member and swinging movement about the end of the carrier which is in registration with the sole to carry the end of the sole past the applying member.

5. A machine of the class described having, in combination, a container for liquid, a liquid-applying member supplied therefrom, a carrier, driving means therefor, means adjustably connected to the carrier for gripping a shoe part and holding it in operative relation to the liquid-applying member, and means for disconnecting the gripping means from the carrier and for disconnecting the carrier from its driving means to permit relative adjustment of the carrier and the gripping means.

40 6. A machine of the class described having, in combination, a container for liquid, a liquid-applying member supplied therefrom, a carrier, driving means therefor, means adjustably connected to the carrier for gripping a shoe part and holding it in operative relation to the liquid-applying member, and means for disconnecting the gripping means from the carrier and for disconnecting the carrier from its driving means to permit relative adjustment of the carrier and the gripping means while the machine is at rest and for reconnecting these parts prior to the starting of the machine.

7. A machine of the class described having, in combination, a container for liquid, a liquid-applying member supplied therefrom, a carrier, driving means therefor, means adjustably connected to the carrier for gripping a shoe part and holding it on edge in operative relation to the liquid-applying member, and means for disconnecting the gripping means from the carrier and for disconnecting the carrier from its driving means to permit adjustment of the carrier with respect to the gripping means.

8. A machine of the class described having, in combination, a container for liquid, a liquid-applying member supplied therefrom, a carrier, driving means therefor, means adjustably connected to the carrier for gripping a shoe part and holding it in operative relation to the liquid-applying member, a catch for holding the gripping means stationary while the machine is at rest, and means for disconnecting the gripping means from the carrier and for disconnecting the carrier from its driving means to permit adjustment of the carrier with respect to the gripping

means while the machine is at rest, and for reconnecting these parts and freeing the gripping means for movement with the carrier prior to the starting of the machine.

9. A machine of the class described having, in combination, a container for liquid, a liquid-applying member supplied therefrom, a carrier, driving means therefor, means adjustably connected to the carrier for gripping a shoe part and holding it on edge in operative relation to the liquid-applying member, a catch for holding the gripping means stationary with respect to the machine while the machine is at rest, and means for disconnecting the gripping means from the carrier and for disconnecting the carrier from its driving means to permit adjustment of the carrier with respect to the gripping means while the machine is at rest, and for reconnecting these parts and freeing the gripping means from its catch prior to the starting of the machine.

10. A machine of the class described having, in combination, a container for liquid, a liquid-applying member adapted to receive liquid therefrom, means for holding a shoe part in operative relation to said member and for imparting to said shoe part a cycle of movement in a manner to cause the margin along two edges and an end of the shoe part to be coated with liquid, and means for thereafter imparting to the shoe part a second cycle of movement in a direction reverse to that of the first cycle while maintaining the operative relation between the shoe part and the applying member thereby to cause a second coat to be applied over the first coat.

11. A machine of the class described having, in combination, a container for liquid, a liquid-applying member adapted to receive liquid therefrom, a carrier for moving the margin of a shoe part such as a sole past said applying member in operative relation thereto, driving means rotating in one direction to move the carrier and the shoe part through a cycle of movement, and means for automatically reversing the direction of rotation of the driving means to impart a second cycle of movement to the carrier and shoe part in a direction reverse to that of the first cycle while maintaining the operative relative between the shoe part and the applying member.

12. A machine of the class described having, in combination, a treating member to the action of which the margin of a shoe sole is subjected, means for imparting to the sole a cycle of movement including movement of translation to treat the side margins and angular movement to treat the end margin, and means for thereafter imparting to the sole a second cycle of movement in the same path as that of the first cycle but in a reverse direction.

13. A machine for treating the margin of one face of a sole which comprises means for holding the sole in a position such that the face of the sole diverges from the horizontal so that liquid applied to the lower margin will run down toward the lower edge of the sole, means for applying liquid to said sole margin at an applying position, and means constructed and arranged to move the sole longitudinally, angularly and again longitudinally to bring successive portions of the margin of the sole into liquid-receiving position.

14. A machine for applying softener to the cement-coated margin of a face of a sole which comprises a softener applying means, a fixed guide adjacent thereto, means for loosely grasp-

- ing one end of the sole to hold it in a position such that it diverges from the horizontal, means for moving the grasping means to drag the edge of the sole over said fixed guide as the softener 5 is applied to the lower margin of the sole adjacent to the guide, and means for controlling said moving means to cause it to impart an angular movement to the sole thereby to treat the toe end thereof.
- 10 15. In a machine for treating a shoe sole for incorporation in a shoe to which the sole is attached chiefly by cement, said sole having a band of cement around the margin of the attaching face of the sole which has been allowed to dry, comprising a solvent applicator, means for holding the sole so that it diverges from the horizontal, and means for causing relative traversing movement between the sole and the solvent applicator to present a marginal portion of uniform 20 width to the applicator thereby applying an excess of liquid solvent to the cemented area in the lower margin of the sole progressively during such traversing movement and allowing the excess solvent to drain from the sole without wetting the tread surface thereof.
16. A machine of the class described having, in combination, a container for liquid, a liquid-applying member supplied therefrom, a movable work carrier adapted to present a piece of work 30 to said applying member, a gage opposite said applying member, spaced guide fingers located before and beyond said applying member with respect to the direction of movement of the work, said work carrier having means for loosely gripping one end of a piece of work having a rounded 35 free opposite end, and means for moving said carrier to move the edge of the work along said gage past said applying member for the application of liquid to a marginal portion of the work 40 and to turn the work with the rounded end resting on the guide fingers whereby the position of the work with respect to the applying member is maintained throughout its range of movement.
17. A machine of the class described having, in combination, liquid-applying means, means for moving a shoe part past said means in operative relation thereto including swinging the shoe part about a rounded end thereof, and means acting 45 temporarily to engage the edge of the shoe part adjacent to the rounded end in a plurality of localities to facilitate supporting the shoe part during the swinging movement.
18. A machine of the class described having, in combination, liquid-applying means, means for moving a shoe part past said means in operative relation thereto including swinging the shoe part about an end thereof, and means operating temporarily to engage an edge of the shoe part adjacent to said end to facilitate the accurate swinging of said shoe part. 5
19. A machine of the class described having, in combination, liquid-applying means, a shoe part 10 carrier having one end in register with one end of the shoe part, means for moving the carrier including means for swinging it about that end which is in register with one end of the shoe part, and an edge guide moved by the carrier in its 15 swinging movement into engagement with an edge of the shoe part to facilitate the accurate swinging of said part.
20. A machine of the class described having, in combination, a treating tool, a gage positioned 20 adjacent to said treating tool in a fixed relation thereto, spaced fingers located upon opposite sides of said gage and movable into and out of operative relation to the work, a carrier mechanism for a piece of work, said work piece having a rounded 25 end, said carrier mechanism being constructed and arranged to grip loosely the work at a position spaced from the rounded end of the work and movable to drag the edge of the work over said gage past said treating tool and to turn the 30 work to bring its rounded end into position for the operation of the tool, and means responsive to movement of said carrier mechanism for moving said fingers into operative position to engage the rounded end of the work. 35
21. A machine of the class described having, in combination, a tool for treating the margin of a sole, a movable sole carrier for presenting the side and end margins of the sole to the tool while maintaining the sole substantially upright, a 40 gage adjacent to said treating tool, movable sole edge engaging guides located before and beyond said treating tool with respect to the direction of movement of the work, said sole carrier loosely gripping one end of the sole and movable to guide 45 the edge of the sole across said gage and to turn the sole with the rounded end resting loosely on the gage, and means on the carrier for moving said guides into engagement with the sole near its end during the turning movement of the carrier. 50

SIDNEY J. FINN.
